PADLOCK

Lawrence E. Harbison, Globe, Ariz.

Application August 12, 1947, Serial No. 768,231

3 Claims. (Cl. 70—38)

1

This invention relates to a padlock.

It is a principal object of this invention to provide a new and improved padlock, wherein a plurality of cylinders may be selectively arranged to permit operation of the lock by a key having a particular configuration. While this invention is shown applied to a padlock, it is obvious that other forms of locks may be similarly improved.

A preferred embodiment of the invention is illustrated in the accompanying drawings, but it is understood that modifications may be made therein without departing from the spirit of the invention as hereinafter claimed.

Figure 1 represents a vertical longitudinal section through the new and improved padlock.

Figure 2 is a bottom plan view.

Figure 3 is a horizontal section, taken along the line 3—3 of Figure 1.

Figure 4 is a horizontal section, taken along the line 4—4 of Figure 1.

Figure 5 is an enlarged vertical section, taken along the line 5—5 of Figure 2.

Figure 6 is a horizontal section, taken along the line 6—6 of Figure 5.

Figure 7 is an enlarged horizontal section, taken along the line 7—7 of Figure 1.

Figure 8 is a bottom plan view, on an enlarged scale, of a portion of the lock when the key is applied thereto.

Figure 9 is a front elevation of the key shown in Figure 8.

As illustrated in the drawings, the new and improved lock comprises a housing 10 of generally conventional form. The housing 10 is suitably apertured at one side to receive a shackle 11. A spring 13 bears against the bottom of the shackle 11 to urge it outwardly, and a stop 15 fixed in the housing 10 limits the upward movement of the shackle 11.

The shackle 11 has two horizontal slots 16 and 17 for the reception of two bolts 18 and 19, respectively. When the bolts 18 and 19 are retracted, the spring 13 will urge the shackle 11 upwardly to open position.

The housing 10 is bored to receive a sleeve 20. The sleeve 20 is centrally apertured to receive a series of four cylinders 21, 22, 23, and 24, these cylinders being concentrically arranged in nested relation about a vertical rod 25. The upper extremity 26 of the rod 25 is threaded. Underneath the threaded portion 26 is a circular portion 27. Then comes a portion 28 that is triangular in cross-section, as indicated in Figure 6 of the drawings. The central portion 29 of the rod 25 is substantially enlarged, the portion 30 underneath the

2

enlarged portion 29 being of the same circular cross-section as the portion 27. The lower extremity 31 of the rod 25 is again triangularly-shaped, for a purpose to be described more particularly hereinafter.

The cylinders 21, 22, 23, and 24 are made in semi-cylinders, for ease of manufacture and assembly, and are held in position about the rod 25 by a series of split annular springs 33, 34, 35, and 36. Each of the springs 33, 34, 35, and 36 encircles its respective cylinder 21, 22, 23, and 24 about the region of the enlarged portion 29 of the rod 25 in such a way as to leave a slight space between each spring and its outer cylinder. Each of the springs 33, 34, 35, and 36 has a raised notch 38 on one side of its upper edge, and a horizontal bar 40 is accommodated in the notches 38 to prevent relative movement of the springs. At the same time, the cylinders 21, 22, 23, and 24 are retained frictionally, but are movable with respect to one another by means to be described more particularly hereinafter.

Each of the cylinders 21, 22, 23, and 24 has a vertical protrusion 41, 42, 43, and 44, respectively, on its lower surface. The intermediate portions of the cylinders 21, 22, 23, and 24 are offset inwardly toward the rod 25, as indicated in Figure 5 of the drawings, so that when assembled there can be no relative vertical movement. The protrusions 41, 42, 43, and 44, as well as the lower extremity 31 of the rod 25, project below the lower surface of the housing 10, as indicated in Figure 1 of the drawings, and are operable by a key 45 to rotate the cylinders 21, 22, 23, and 24, as well as the rod 25, to a pre-selected position to retract the bolts 18 and 19 from the grooves 16 and 17, respectively, in the housing 10, to release the shackle 11.

The sleeve 20 has a plurality of windows extending horizontally thereof through which wedges 46 may be passed to engage the radially-offset portions of the outermost cylinder 21, and thereby lock all the cylinders and their springs in position.

The two sides of the sleeve 20 have projecting ears 50 and 51 which are suitably apertured to receive a spacer 52 surrounding the upper portion of the outermost cylinder 21. One side of the spacer 52 has a square hole to receive a lug 57 having a square cross-section to fit within the hole. The lug 57 has a horizontal projection 58. On the opposite side of the spacer 52 there is an abutment 80, Figures 6 and 7, which has an inclined surface 81.

A rotary disc 60 is mounted on the round por-

tion 27 of the rod 25, the disc 60 being slideable on the rod 25. A leaf spring 53 is held in place on the side of the rotary disc 60, and normally rests against the extension 58 of the lug 57, thereby preventing rotation of the disc 60. The function of this is to prevent intersleeve friction from overcoming the coil spring 61. The intersleeve friction arises from the interaction of the cylinders 21, 22, 23, and 24 against the cylindrical springs 33, 34, 35, and 36, which springs, in turn, are connected to the bar 40. This bar 40 has a vertical portion 54 slideable vertically in a hole 55 in the disc 60, but also exerts a rotary force on the disc 60 by virtue of the eccentricity of the hole 55. A coil spring 61 joins the extension 58 of the lug 57 to the disc 60 by means of two set screws 63 and 64, this spring 61 normally resisting rotation of the disc 60 with respect to the lug 57. Another coil spring 65, mounted on the upper end of the rod 25 and held thereto by means of a nut 66 engaged with the threaded portion 26 of the rod 25, normally urges the disc 60 downwardly. Two bolts 68 and 69 project vertically from the upper surface of the disc 60, and two connecting rods 71 and 72 are pivoted thereto. The lock bolts 18 and 19 are fastened to the ends of the connecting rods 71 and 72, respectively. It will be seen, therefore, that when the disc 60 is rotated, the connecting rods 71 and 72 will likewise be rotated about the axis of the rod 25, and operate to retract the lock bolts 18 and 19 from their recesses 16 and 17 in the housing 10. As will be observed from Figure 3 of the drawings, the connecting rods 71 and 72 are slightly curved to permit radial movement of the bolts 18 and 19 as the inner ends of the connecting rods 71 and 72 are rotated about the axis of the rod 25.

The disc 60 is provided on its under side with a plurality of pins 90, which are arranged in a pre-arranged fashion in accordance with the combination of the lock. Depending from the disc 60 adjacent the outermost one of the pins 90 is a cam 91, the cam being of a length greater than the length of the triangular portion 28 of the rod 25 and of the exposed portions of the pins 90 when the latter are in the apertures of the cylinders 21, 22, 23 and 24. The upper peripheries of the cylinders 21, 22, 23, and 24 are suitably apertured to receive the pins 90.

In the operation of the device, the key 45 is mounted on a triangular end 31 of the rod 25, as indicated in Figure 8, of the drawings, and rotated clockwise against the protrusions 41, 42, 43, and 44, the key 45 bearing the proper indentations to operate the lock. As the protrusions 41, 42, 43, and 44 are rotated about the axis of the rod 25, they will, of course, rotate with them their cylinders 21, 22, 23, and 24. The rotary disc 60 is on the round portion 27 of the rod 25 and does not rotate. As soon, however, as the cylinders 21, 22, 23, and 24 have been aligned by the rotation of the key 45 so that the pins 90 may enter their apertures in the upper ends of the cylinders, the spring 65 will force the disc 60 downwardly so that the pins 90 enter the apertures in the cylinders. The spring 53 will drop below the extension 58 of the lug 57, permitting the disc 60 to be rotated clockwise. The axial movement of the disc will bring it onto the triangular portion 28 immediately underneath the round portion 27 of the rod 25. Continued rotation of the key 45 will now result in rotation of the rotary disc 60, and this will actuate the connecting rods 71 and 72 to withdraw the lock bolts 18 and 19 from their

recesses 16 and 17, so that the shackle 11 will be released.

To lock the padlock, the ends of the shackle 11 are inserted in the openings of the housing 10, and while held in such inserted position, the key 45 is mounted on the triangular end 31 of the rod 25, and rotated clockwise. Rotation of the key 45 causes further rotation of the disc 60 until the cam 91 carried by the disc 60 engages the inclined surface 81 of the abutment 80 carried by the spacer 52. Further rotation of the key 45 causes the cam 91 of the disc 60 to ride upwardly along the inclined surface 81 of the abutment 80, resulting in advancing the disc toward the circular portion 27 of the rod 25 against the action of the spring 65, until finally the disc 60 is no longer in engagement with the triangular portion 28 of the rod 25 and the pins 90 carried by the disc 60 are out of engagement with the apertures in the cylinders 21, 22, 23 and 24. When the disc 60 is free of engagement with the triangular portion 28 of the rod 25 it is returned to its normal spaced position with respect to the spacer 52 by means of the spring 61. This action of the spring 61 causes the disc 60 to rotate and actuate the rods 71 and 72, resulting in the lock bolts 18 and 19 to engage with the recesses 16 and 17 in the shackle 11. It is to be noted that the rotation of the disc 60 caused by the spring 61 is continued until leaf spring 53 has passed extension 58 of the lug 57 and the spring 61 has become slack after its retraction. When the lock bolts 18 and 19 are in engagement with the recesses 16 and 17 in the shackle 11, the shackle is then freed of its held position.

I claim:

1. In a padlock, a housing, a shackle projecting from one end face of said housing and mounted for inward and outward movement longitudinally in the latter, a rotatable cylindrical rod arranged longitudinally within said housing and having an end projecting out of the other end face of said housing, said rod having an enlarged cylindrical portion intermediate its ends and a portion of non-circular cross-section at one end of the enlarged portion, the non-circular cross-sectional portion having one end abutting the adjacent end of said enlarged portion and being spaced from the end of the rod opposite the projecting end of the latter, a plurality of rotatable cylinders concentrically arranged in nested relation about the enlarged cylindrical portion of said rod, each of said cylinders being provided with a depending protrusion on the end adjacent the projecting end of said rod, the respective protrusions projecting out of the said other end face of said housing, there being an aperture in each of said cylinders in the end face opposite the projecting end of said rod, a bar straddling the end faces of the respective cylinders opposite the projecting end of said rod and carried by the cylinders, a rotatable disc on the portion of said rod adjacent the other end of said non-circular cross-sectional portion which is mounted for slideable movement into and out of engagement with said non-circular cross-sectional portion, a plurality of pins arranged in spaced relation and projecting from the end face of said disc adjacent the projecting end of said rod, said pins being receivable in the apertures of said cylinders when the latter have been rotated to a position such that the apertures in the cylinders are in registry therewith, means projecting from said bar and slidably extending through said disc, opposed aligned bolts connected to the other end

face of said disc and mounted for movement transversely into and out of engagement with said shackle, and resilient means connected to the end of the rod opposite its projecting end and to said disc for urging the latter toward the non-circular cross-sectional portion of said rod.

2. In a padlock, a housing, a shackle projecting from one end face of said housing and mounted for inward and outward movement longitudinally in the latter, a rotatable cylindrical rod arranged longitudinally within said housing and having an end projecting out of the other end face of said housing, said rod having an enlarged cylindrical portion intermediate its ends and a portion of non-circular cross-section at one end of the enlarged portion, the non-circular cross-sectional portion having one end abutting the adjacent end of said enlarged portion and being spaced from the end of the rod opposite the projecting end of the latter, a plurality of rotatable cylinders concentrically arranged in nested relation about the enlarged cylindrical portion of said rod, each of said cylinders being provided with a depending protrusion on the end adjacent the projecting end of said rod, the respective protrusions projecting out of the said other end face of said housing, there being an aperture in each of said cylinders in the end face opposite the projecting end of said rod, a bar straddling the end faces of the respective cylinders opposite the projecting end of said rod and carried by the cylinders, a rotatable disc on the portion of said rod adjacent the other end of said non-circular cross-sectional portion which is mounted for slidable movement into and out of engagement with said non-circular cross-sectional portion, a plurality of pins arranged in spaced relation and projecting from the end face of said disc adjacent the projecting end of said rod, said pins being receivable in the apertures of said cylinders when the latter have been rotated to a position such that the apertures in the cylinders are in registry therewith, means projecting from said bar and slidably extending through said disc, opposed aligned bolts connected to the other end face of said disc and mounted for movement transversely into and out of engagement with said shackle, a coiled spring connected to the end of the rod opposite its projecting end and to said disc for urging the latter toward the non-circular cross-sectional portion of said rod and interengaging means on said housing and said disc for normally maintaining the latter against rotation.

3. In a padlock, a housing, a shackle projecting from one end face of said housing and mounted for inward and outward movement longitudinally in the latter, a rotatable cylindrical rod arranged longitudinally within said housing and

having an end projecting out of the other end face of said housing, said rod having an enlarged cylindrical portion intermediate its ends and a portion of non-circular cross-section at one end of the enlarged portion, the non-circular cross-sectional portion having one end abutting the adjacent end of said enlarged portion and being spaced from the end of the rod opposite the projecting end of the latter, a plurality of rotatable cylinders concentrically arranged in nested relation about the enlarged cylindrical portion of said rod, each of said cylinders being provided with a depending protrusion on the end adjacent the projecting end of said rod, the respective protrusions projecting out of the said other end face of said housing, there being an aperture in each of said cylinders in the end face opposite the projecting end of said rod, a bar straddling the end faces of the respective cylinders opposite the projecting end of said rod and carried by the cylinders, a rotatable disc on the portion of said rod adjacent the other end of said non-circular cross-sectional portion which is mounted for slidable movement into and out of engagement with said non-circular cross-sectional portion, a plurality of pins arranged in spaced relation and projecting from the end face of said disc adjacent the projecting end of said rod, said pins being receivable in the apertures of said cylinders when the latter have been rotated to a position such that the apertures in the cylinders are in registry therewith, means embodying a pin projecting from said bar and slidably extending through said disc, opposed aligned bolts connected to the other end face of said disc and mounted for movement transversely into and out of engagement with said shackle, a coiled spring connected to the end of the rod opposite its projecting end and to said disc for urging the latter toward the non-circular cross-sectional portion of said rod and inter-engaging means on said housing and said disc for normally maintaining the latter against rotation, said inter-engaging means including a projecting lug carried by said housing and a leaf spring projecting from the periphery of said disc engaging said projecting lug.
